UNITED STATES PATENT OFFICE.

LOUIS RIBAR, OF DETROIT, MICHIGAN.

BED-TABLE.

1,140,397.

Specification of Letters Patent. Patented May 25, 1915.

Application filed August 8, 1914. Serial No. 855,398.

To all whom it may concern:

Be it known that I, LOUIS RIBAR, a subject of the King of Hungary, residing at Detroit, in the county of Wayne and State of Michigan, have invented certain new and useful Improvements in Bed-Tables, of which the following is a specification, reference being had therein to the accompanying drawings.

10 This invention relates to an attachment for beds, cots, couches and similar structures, and more particularly to a novel table, platform or book rest that can be swung over the side of a bed or similar structure 15 for the convenience of the occupant of the bed.

The primary object of my invention is to provide a table of the above type that is supported by a novel bracket adapted to be secured to the side rail or post of the bed, the bracket supporting the table whereby it can be easily and quickly swung into position for use over the bed or swung to one side and tilted whereby it will occupy comparatively small space when not in use.

25 A further object of this invention is to provide a table of the above type that is simple, durable, easy to manipulate, and highly efficient as an attachment for beds used in hospitals, sanitariums and similar institutions.

With the above and other objects in view the invention resides in a novel construction, combination and arrangement of parts as hereinafter specifically described and then claimed, and reference will now be had to the drawing wherein—

Figure 1 is a front elevation of the table as attached to a bed and in position for use; 40 Fig. 2 is an enlarged front elevation of the table partly broken away and partly in section; Fig. 3 is an end view of a portion of the table; Fig. 4 is a plan of a clamp forming part of the attachment; Fig. 5 is a front 45 elevation of the table illustrating a modified form of clamp; Fig. 6 is an enlarged plan of the modified form of clamp; Fig. 7 is a side elevation of the same partly broken away and partly in section; and Fig. 8 is a 50 front elevation of the table in tilted position.

Since the attaching of the table to a structure simply depends upon the form of clamp or hold-fast device employed, the above views are merely illustrative of an example 55 whereby my invention may be applied in practice, therefore I would have it under-

stood that the structural elements are susceptible to such changes as fall within the scope of the appended claims.

A preferred form of clamp, such as can be used in connection with the angle bar or side frame 1 of a brass or iron bed 2, is shown in detail in Figs. 2 and 4, the clamp comprising a metallic strap 3 shaped to embrace the sides and bottom of the side frame. The ends 4 and 5 of the strap protrude above the top of the side frame and are provided with notches or recesses 6, at the ends of the clamp, for gates 7 pivotally mounted in the end 5 of the strap, as at 8. The gates 7 serve functionally as latch bars and after the strap has been placed in engagement with the side frame 1, the gates can be swung to a closed position to overlie the top of the side frame and prevent accidental displacement of the clamp while the table is in use. To positively lock the clamp and prevent longitudinal movement thereof upon the side frame, the outer side of the clamp or the end 5 thereof is provided with a winged thumb screw 9 adapted to be screwed into engagement with the side frame.

Intermediate the ends of the clamp there is an integral upwardly extending bracket 10 provided with a vertically disposed barrel 11. The barrel 11 affords a bearing for the base 12 of a compound curved arm 13 and the base of said arm has a stem 14 extending into the barrel and cooperating therewith in providing a swivel for the arm 13. The stem 14 has the lower end thereof tapped or provided with a bore 15 to receive a winged thumb screw 16 said screw extending through a washer 17 at the lower end 90 of the barrel. It is through the medium of the screw 16 that the stem 14 can be locked relative to the barrel to hold the arm 16 in an adjusted position.

The upper end of the arm 13 is bifurcated 100 or slotted, as at 18 and formed with apertured ears 19 and side flanges 20, said side flanges providing a substantial rest for a segment shaped support 21 having a web or rib 22 pivotally mounted between the ears 105 19 by a screw bolt 23 or similar pivotal means. The web or rib 22 is longitudinally disposed and extends into the slot 18 when the support 21 rests upon the upper end of the arm 13. The support 21 is carried by 110 a spider or base frame 24 secured by screws 25 or other fastening means to the bottom

side of a table or platform 26. The table or platform 26 is in the form of a board of any desired shape in plan and of sufficient area to accommodate various articles. The 5 spider 24 at each side of the support 21, has depending apertured ears 27 and pivotally connected to said ears are parallel links 28 extending downwardly at the sides of the arm 13. Extending through the links 28 are 10 the ends of a bolt 29 arranged transversely of the upper end of the arm 13. The ends of the bolt 29 are provided with nuts 30 and spacer sleeves 31, and with the bolt extending through the bifurcation or slot 18 of 15 the arm 13, it is necessary to provide the web or rib with a notch 32, said notch providing clearance for the bolt. The links 28 limit the tilting movement of the table or platform 26 allowing the table or platform to be 20 swung from a horizontal position to a vertical plane, whereby the table or platform will occupy comparatively small space at the side of the bed when not in use.

To prevent the table or platform 26 from 25 accidentally tilting, particularly when articles are placed upon the outer end thereof, the end of the table or platform which projects over the arm 13 is provided with a depending staple 33 to receive a hook 34 forming 30 part of a chain 35 attached to an apertured lug 36 forming part of the arm 13. The chain 35 constitutes a flexible connection for maintaining the table or platform 26 in a horizontal position and said table or 35 platform can be easily released when it is desired to tilt the same.

Reference will now be had to Figs. 5, 6 and 7 showing another form of clamp which permits of the attachment being secured to a 40 post 37 of a bed. The clamp is in the form of a semicylindrical member 38 adapted to engage one side of the post 37, said member having the longitudinal edges thereof provided with channel shaped flanges 39 that 45 taper from the upper end of the member to the lower end thereof, said flanges having the lower ends thereof closed by stops 40.

The shape of the flanges 39 is such as to provide tapering grooves or seats 41 for tapering flanges 42 carried by a semi-cylindrical member 43 that cooperates with the member 38 in forming a sleeve that can be clamping into engagement with the post 37. The member 43 can be wedged into engagement with the post 37 and the member 38 55 and when properly adjusted said members are locked in engagement by a winged thumb screw 44 of the member 43. The member 38 of the clamp has a horizontally disposed curved bracket 45 divided with a vertically 60 disposed barrel 46 similar to the barrel 11 previously described.

From the foregoing it will be observed that I have devised a novel table for invalids that assures certain conveniences for those 65 confined to a bed, and the shape of the base of the arms 13 provides a rack or hanger for a towel and other necessities. When the table or platform is in a horizontal position, the web or rib 22 prevents lateral displacement, and with the stem 14 loose in the barrel 11 the table or platform can be easily swung to one side after being used. The entire attachment can be enameled or finished to harmonize with the bed or structure to which it is attached. 75

What I claim is:—

An attachment for beds comprising a curved arm having the upper end thereof curved and bifurcated, a tiltable segment 80 shaped support normally resting upon said arm, a web carried by said support and extending into the bifurcation of said arm and having an end thereof pivotally held therein whereby said support can be swung away 85 from said arm, and a table carried by said support.

In testimony whereof I affix my signature in presence of two witnesses.

LOUIS RIBAR.
